(57) **CLAIM**

The ornamental design for an electric toothbrush with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of an electric toothbrush with graphical user interface showing my new design.

The dash-dash broken lines in the drawings depict the portions of the electric toothbrush that form no part of the claimed design.
